UNITED STATES PATENT OFFICE.

CARL WILLIAM SCHEDLER, OF BERKELEY, CALIFORNIA.

EVAPORATOR PROTECTOR.

Application filed November 11, 1925. Serial No. 68,255.

This invention relates to a protector for evaporators and its object is to prevent the wear of the steam drum of the evaporator which makes its renewal at great expense a frequent occurrence. It will be understood by those skilled in the art that steam evaporators make use of a large drum which is provided with several hundred small tubes, which drum costs from \$2500.00 to 10 \$3000.00 new and which requires the dismantling of the evaporator to replace the drum, and this not only ties up the plant for a day or two, but is very expensive in addition.

15 In such evaporators as are herein disclosed, the liquid to be evaporated is run into a closed receptacle within which the steam drum is installed and the receptacle is maintained under a vacuum of from ten to 20 twenty five or more, inches of mercury. In order to operate the evaporator at the highest efficiency it is very necessary to have the fresh liquid fed into the evaporator at a certain point, and for some reason, the steam 25 pipe leading to the drum erodes through in a very short time just at the junction thereof with the steam drum, and the steam drum itself erodes through in an equally short time just opposite the end of the feed pipe 30 for the fresh liquid, probably due to rapid evaporation and crystallization of the solids.

I have ascertained that by placing a renewable plate on the drum and a divided renewable sleeve on the steam pipe, both of 35 which can be dismounted and renewed or repaired, by operating through the evaporator manholes, whatever wear there may be on those plates will not affect the steam drum or the steam pipe, with the added benefit of 40 making the replacement a matter of only an hour or two instead of requiring a day or more. In this way the life of the steam drum and the steam pipe leading thereto has been increased four or five times over an 45 ordinary steam drum not so equipped. The wear seems to be due to the sudden expansion of the liquid when it strikes the region of the high vacuum, with the consequent sudden deposit of crystals of the material in 50 solution.

An embodiment of the invention is shown in the accompanying drawings in which the same reference numeral is applied to the same portion throughout the several figures

of the drawings and of which there may be 55 modifications thereof.

Fig. 1 is a vertical sectional view of the evaporator and the steam drum.

Fig. 2 is a plan view of the evaporator with the top section removed, showing the 60 steam drum in plan.

Fig. 3 is a vertical sectional view of a portion of the steam drum showing the steam pipe leading thereto.

Fig. 4 is a side elevation of a portion of 65 the steam drum and steam pipe, showing the protecting plate and pipe covering.

The shell of the evaporator is made up of two lower conical sections 1 and 2, two cylindrical sections 3 and 4, a top section 5, and a special pipe manifold 6 to which the steam pipe 7 is connected and to which the pipes leading to the vacuum pump may be connected. The top member 6 has a flange 9, and all of the parts of the shell are suitably flanged to have the parts connected by bolts 10. The steam pipe 7 passes into the evaporator through a suitable stuffing box 7' at the top of the same.

The bottom 1 has two discharge pipes 12 80 and 13 connected thereto which are controlled by suitable valves, and the shell has manholes 14 and 15 through which the workman can insert and place the new plate and the parts for the steam pipe. The shell 85 3 has the fresh liquid supply pipe connected thereto as shown at 16.

The steam drum has a slightly conical bottom 17 and correspondingly conical top 18, both of which are flanged downwardly and 90 connected to the cylindrical shell 19, and a great number of small tubes 20 connect the top and bottom to give the necessary area for the rapid transference of heat from the drum to the liquid in the evaporator.

The steam drum is ordinarily supported by the steam pipe and by three centering brackets 22, 23 and 24, in turn resting on three lugs 25, 26 and 27 formed on a member 2, while a drill pipe 28 leads to a trap 100 for draining the water out of the steam drum as fast as condensation takes place.

On account of the erosion and rapid destruction of the steam pipe adjacent to drum, it has been common to make use of a 105 short length of pipe as indicated at 29 to avoid the necessity of renewing the entire steam pipe when the drum has to be re-

newed, and with the present invention, the same short section of pipe is used but it is covered with a sectional sleeve consisting of four flanged parts 30, each secured to the adjacent part by means of three bolts 31, and the lower end of which sleeve covers the drum connecting flange and the rivets by which it is connected to the short steam pipe section 29.

- 10 For considerable area in front of the liquid inlet pipe 16 the steam drum itself is protected with a detachable plate 33, which plate has an angle plate 34 secured thereto at its lower edge, and said angle plate has 15 two holes therein to receive the lower ends of two rods 35 and 36 which are passed through two of the tubes of the steam drum, and which are connected by means of two eyebolts 37, and 38, and the two upwardly 20 projecting ears 39 and 40 of the plate 33. The foregoing method of attachment of the plate to the steam drum is especially applicable to those installations where the drum is already in place.
- 25 The manner of ebullition of the liquid through and around the steam drum is indicated by the arrows in Figure 1 and it appears to be necessary to have the fresh liquid inlet pipe at the place indicated to properly 30 maintain this condition, while if it is not

maintained, the operation of the evaporator will be seriously interfered with, and its efficiency greatly reduced.

Having thus described my invention, what I desire to secure by Letters Patent of the United States, is as follows, but modifications may be made in carrying out the invention as shown in the drawings and in the above particularly described form thereof, within the purview of the annexed claim.

In an evaporator having a shell and a steam drum disposed therein, said steam drum comprising a steam chamber traversed by substantially vertical liquid tubes, and said shell having its liquid inlet disposed between the planes bounding the top and the bottom of said drum, a detachable plate between said drum and said liquid inlet of said plate having two upwardly extending ears, eyebolts in said ears, rods engaging said eyebolts and passing through tubes in said steam drum, an angle plate on the bottom of said detachable plate, and holes in said angle plate receiving the lower end of said rods.

In testimony whereof I have hereunto set my hand this 5th day of November A. D. 1925.

CARL WILLIAM SCHEDLER.
